UNITED STATES PATENT OFFICE.

GEORGE H. FORSYTH, OF CHICAGO, ILLINOIS.

WINDOW-SCREEN.

1,274,029.

Specification of Letters Patent.

Patented July 30, 1918.

Application filed August 9, 1916. Serial No. 113,873.

To all whom it may concern:

Be it known that I, GEORGE H. FORSYTH, a citizen of the United States, residing at Chicago, in the county of Cook and State 5 of Illinois, have invented certain new and useful Improvements in Window-Screens, of which the following is a specification.

The invention relates particularly to the adaptation of a screen for convenient assembly and use in connection with the sliding sash of railway cars, by the provision of simple and efficient means enabling the screen to be raised from a lowered operative position covering the window opening when 10 the sash is raised to an elevated inoperative position between the two sashes and above the line of vision through the lower sash.

Heretofore it has been usual to employ a hook or similar device to reach between the 20 two sashes and engage the screen in its elevated position to pull the same down within reach of the operator, but recognizing the liability of injury to the screen while "fishing" for it with the hook, as also the inconvenience attending such manipulation, it has been thought to avoid the necessity of using any extraneous tool in operating the screen, and it is to the accomplishment of this purpose that the present invention is more particularly directed.

Another feature of the invention is the provision of a metal frame for screens which embodies an improved and highly efficient arrangement for securing the wire cloth in 35 the frame and for attaching a weather striping thereto.

A further feature is the peculiarly advantageous mounting of the screen lock, whereby to enable the same to be readily removed 40 from and reassembled with the screen frame.

In order that the invention may be readily understood a preferred embodiment of the same together with modifications of certain portions is set forth in the accompanying 45 drawing and in the detailed description predicated thereon. Obviously, however, the invention is susceptible of embodiment in other and varied constructional forms without departure from the spirit and essence thereof, wherefore the drawings and description are to be taken in an illustrative and not in an unnecessarily limiting sense. In the drawings—

Figure 1 is a front elevation of a window

provided with the screen, the same being 55 broken in portions in order to conveniently show the same;

Fig. 2 is a similar view of one side of the window and screen showing the latter in 60 partially lowered position;

Fig. 3 is a fragmentary view of a window frame and screen showing the latter in its lowered position;

Fig. 4 is a detail transverse sectional view on the line 4—4 of Fig. 3;

Fig. 5 is a horizontal section taken substantially on the line 5—5 of Fig. 2, but showing the two sashes and the screen frame in substantially the same horizontal relation;

Fig. 6 is a partial vertical section through the upper corner of the screen frame showing the mounting of the lock;

Figs. 7, 8, 9 and 10 are cross sectional views through the screen frame showing the 75 mounting of the upper weather strip, the lower weather strip and modified forms of screen frame construction.

Having reference to the drawings more in detail, the upper sash is indicated at 11, 80 the lower sash at 12 and the screen frame at 13. These sashes are guided in the spaces between the stops 14, 15 and an intermediate stop 16, by which they are horizontally spaced apart a distance corresponding to the 85 thickness of the stop 16, and when both are in elevated position they form therebetween a vertically disposed pocket within which the screen frame 13 is received. In order to provide for the movement of the screen 90 frame from within the pocket to a position accessible to the operator, a particular form of mounting for the screen frame is provided which will now be described.

Upon the stop 16 at each side of the window opening is formed, preferably integral therewith, a guide member 17 which, as herein shown, is substantially cylindrical in cross section. These guides 17 extend the full height of the window opening between 95 the upper and lower sashes 11 and 12. Slidably engaging the guides 17 are shoes 18 each of which is so bent as to envelop the cylindrical portion of the guide in such manner as to prevent disassociation while permitting of free sliding movement. Each of the shoes 18 has above a terminal flange portion 19 and below a similar flange por-

tion 20 projecting inwardly at right angles therefrom to provide a handle for manual manipulation. These shoes 18 are of a length considerably less than the total 5 height of the window opening and sufficiently greater than the height of the sashes and consequently of the pocket formed between the sashes to project therefrom, as indicated in Fig. 1, thus permitting the 10 flanged terminal portion 20 to be grasped by the operator when the screen frame is in its uppermost position.

The screen frame is provided on its two 15 vertical edges with a channel to receive the shoe 18, the channel on one side of the screen frame being so arranged as to receive a bow spring 21 which bears on the shoe so as to provide, as is usual, for lateral yielding.

It will be observed that the left hand 20 guide 17 is in its upper portion provided with a recess 22 having a lower oblique wall and in its lower portion with a recess 23 having an abrupt wall for the reception of the head 24 of the bolt lock, the detailed 25 construction of which will be hereafter more clearly set forth. It will also be observed that the shoe 18 is near its upper end provided with an aperture 25 into which the material of the shoe is bent at an inclination 30 on the lower side, and at another portion of its length the shoe 18 is provided with an aperture 26 which in the lowered position of the window screen coincides with the recess 23 of the guide. The apertures 25 and 35 26 serve as a passageway through which the bolt 24 may enter the recesses 22 and 23 of the guide. The recess 23 of the guide having abrupt walls serves to positively lock the screen in its lowered position by means 40 of the bolt 24 whereas the recess 22 having a lower oblique wall provides a frictional locking only of the sash and permits the bolt to ride out of the recess upon force being applied in a downwardly direction 45 upon the side frame.

From the above it will be readily apparent that the shoes 18 have a limited sliding movement upon the guides 17, such range of movement being less than the total length 50 of the guides, and that in turn the screen frame has a sliding movement upon the shoes limited only by the flanged terminal portions 19 and 20.

If now we assume the screen frame to be 55 in its uppermost position as shown in Fig. 1, housed entirely within the pocket formed between the upper and lower sash, the handles 20 project from the shoes within easy reach of the operator. He grasps the handles 20 on each side of the window casing and exerts a downward pull. This causes the bolt head 24 to ride out of the recess 22 and to bear on the face of the guide as the screen and shoes move downwardly. This 60 movement continues until the screen frame

comes within the reach of the operator who then grasps the frame and continues the downward pull until the handles 20 of the shoes strike against the window sill snapping over the studs 27 at the lower ends of 70 the guides. A further pull on the screen frame causes the bolt head 24 to ride out of the recess 25 onto the surface of the shoe itself and the further downward movement of the screen is independent of the shoes 75 which at this time are stationary. When the bolt 24 reaches the recesses 26 and 23 which are in alinement it snaps through the aperture 26 into the recess 23 and locks the screen against being raised from the outside. 80

The screen being in the lowered position, the operator takes hold of the same by means of the recessed grip 28 and lifts the frame until its upper edge contacts the flange 19, thereupon the further upward movement of 85 the screen frame disengages the lower flange 20 from the stud 27 and the shoes 18 travel upwardly with the screen frame. As soon as the lower edge of the screen frame passes within the pocket between the elevated 90 sashes the operator transfers his hold to the handles 20 and continues the upward movement of the frame into the pocket until the upper ends of the shoes bearing the flanges 19 strike the top of the window casing, at 95 which time the bolt 24 will snap through the aperture 25 into the recess 22 and frictionally hold the screen in its elevated position entirely within the pockets between the two sashes. It is understood, of course, that before starting the upward movement of the screen the operator will have released the bolts 24 from the recess 23 by pressing outwardly upon the lever handles 29 whereby the bolt head is retracted through the engagement of its slotted pin 30 with the lever arm 31. 100

This screen lock has particular advantages in that its members may be readily disassociated and removed from the frame 110 and as easily reassembled. The bolt 24 is slidably mounted within the bore 32 and outwardly pressed by means of a compression spring 33 bearing upon the bolt head and inwardly upon the end of the bore. The stem 115 30 projects from the bore into the interior of the screen frame and is slotted at 34 to receive the slightly hooked end 35 of the lever arm 31. If it is desired to remove the bolt for any reason, it is pressed back against 120 the action of the spring 33 and the screw 36 having been removed, the lever 31 is disengaged from the slotted end of the stem and removed through the opening 37 whereupon the bolt 24 and spring 33 may be readily 125 removed from the bore within which they are normally seated. They are re-assembled as easily by a reversal of the operation just described.

In Fig. 7 is shown a convenient mode of 130

assembling an upper weather stripping in the screen frame. To this end the upper edge of the frame is channeled as indicated in this figure, the rubber stripping 38 is laid across the channel and the T strip 39 is utilized to press the strip into the channel by means of its stem 40. It will be noted that the stem 40 is made of two portions, resilient in character and slightly convex so as to yield when passing through the constricted entrance to the channel to expand therein so as to hold the rubber weather stripping securely in position as clearly indicated in said figure.

In Fig. 8 the lower edge of the screen frame is shown as provided with a longitudinally extending channel at 41 adapted to receive the edges of the folded over weather stripping 42, a key 43 being inserted to hold the same frictionally in place. It will be noted that in the preferred form of construction shown in this figure one side of the channel 41 is slightly corrugated at 44 and the key is provided with a similar corrugation by means of which the rubber strip 25 is forced into the first named corrugation, thereby presenting additional resistance to the accidental dislodgment of the strip.

In Figs. 7, 8, 9 and 10 are illustrated in cross section different forms of metallic frame especially adapted for utilization in the making up of screen frames. In Figs. 7 and 8 the channel 45, in which the netting 46 is clamped by means of the rods 47, has its bottom portion longitudinally corrugated 35 at 48 whereby to lend an increased resiliency to the walls of said channel thus permitting said channel to yield as the rod 47 is forced into the same and thereby attaining a much more efficient locking of the 40 wire netting within said channel.

In Fig. 9 this resiliency of the channel 45 is imparted by forming another independent channel alongside the channel 45. This last named channel 48 imparts to the 45 wall intervening between it and the channel 45 a yielding quality which conduces to the secure clamping of the screen cloth.

In Fig. 10 the main body of the screen frame has inserted therein a stiffening member 49 and the thin metal of the frame extends therefrom in an L-projection 50. Between the terminus thereof and the main wall of the frame is formed a channel 51 the walls of which have great relative resiliency 55 for the secure clamping of the screen cloth 46 by means of the rods 47.

I claim:

1. The combination of a window casing, spaced members providing a pocket therebetween, guides disposed in line with and entering said pocket, shoes sliding on said guides and having a range of movement less than the length of the guides, a frame member riding on the shoes and also slidale 60 thereon, the shoes having terminal portions

forming stops for the frame member, and releasable means to lock the frame to the shoes and the shoes to the guides.

2. The combination of a window casing, horizontally spaced members providing a vertical pocket therebetween, vertical guides disposed in line with and entering said pockets, shoes sliding on said guides and having a range of movement less than the guides, a frame member riding on the shoes and also slidale 70 thereon, the shoes having terminal portions forming stops for the frame member, and releasable means to lock the frame to the shoes and the shoes to the guides. 75

3. The combination of a window casing, horizontally spaced members providing a vertical pocket therebetween, vertical guides disposed in line with and entering said pockets, shoes sliding on said guides and having a length greater than the depth of 80 the pocket and a range of movement less than the length of the guides, a frame member riding on the shoes and also slidale thereon, the shoes having terminal portions forming stops for the frame member, and releasable means to lock the frame to the shoes 85 and the shoes to the guides. 90

4. The combination of a window casing, horizontally spaced members providing a vertical pocket therebetween, vertical guides 95 disposed in line with and entering said pockets, shoes sliding on said guides and having a range of movement less than the guides, a screen frame member riding on the shoes and also slidale thereon, the shoes having terminal portions forming stops for the frame member, and releasable means to lock the frame to the shoes 100 and the shoes to the guides.

5. The combination of a window casing, horizontally spaced members providing a vertical pocket therebetween, vertical guides disposed in line with and entering said pockets, shoes sliding on said guides and having a length greater than the depth of the 105 pocket and a range of movement less than the length of the guides, a screen frame member riding on the shoes and also slidale thereon, the shoes having terminal portions forming stops for the frame member 110 and handles for manual engagement, and releasable means to frictionally lock the frame to the shoes and the shoes to the guides. 115

6. The combination of a window casing, horizontally spaced members providing a vertical pocket therebetween, vertical guides disposed in line with and entering said pockets, shoes sliding on said guides and having a length greater than the depth of the 120 pocket and a range of movement less than the length of the guides, a screen frame member riding on the shoes and also slidale thereon, the shoes having terminal portions forming stops for the frame member 125 130

and handles for manual engagement, and releasable means to frictionally lock the frame to the shoes and the shoes to the guides in the upper position of the screen frame and to positively lock the frame to the shoes and the shoes to the guides in the lowered position of the screen frame.

7. The combination of a window casing, horizontally spaced sash members providing a vertical pocket therebetween, vertical guides disposed in line with and entering said pockets, shoes sliding on said guides and having a length greater than the depth of the pocket and a range of movement on the guides less than the length of the guides, a screen frame member riding on the shoes and also slidably thereon, the shoes having terminal laterally extending flanges forming stops for the frame member and handles for manual engagement, means to frictionally lock the shoes to the guides in their lowermost position, and manually releasable means to frictionally lock the frame to the shoes and the shoes to the guides in the upper position of the shoes and frame and to positively lock the frame to the shoes and the shoes to the guides in the lowered position of the shoes and frame.

8. A metal frame for screens having continuous walls provided in one side face with a channel adapted to receive the marginal portion of the screen cloth and a cloth-clamping rod, one wall of the channel being so formed as to increase its flexibility.

9. A metal frame for screens having continuous walls provided in one side face with a channel adapted to receive the marginal portion of the screen cloth and a cloth-clamping rod, one wall of the channel having formed therein a longitudinal corrugation whereby to increase its flexibility.

10. A metal frame for screens having continuous walls provided in one side face with a channel adapted to receive the marginal portion of the screen cloth and a cloth-clamping rod, and a second channel formed alongside the clamping channel whereby to increase the flexibility of the adjacent wall of the first named channel.

In testimony whereof I have hereunto signed my name in the presence of two subscribing witnesses.

GEORGE H. FORSYTH.
